UNITED STATES PATENT OFFICE.

JOHN B. McCORMICK, OF CHESTER, PENNSYLVANIA.

STEAM-TURBINE.

1,264,132.

Specification of Letters Patent. Patented Apr. 23, 1918.

Application filed September 27, 1917. Serial No. 193,422.

To all whom it may concern:

Be it known that I, JOHN B. McCORMICK, a citizen of the United States, residing in the city of Chester, county of Delaware, 5 and State of Pennsylvania, have invented certain new and useful Improvements in Steam-Turbines, of which the following is a specification.

My invention relates to that type of steam turbines in which is employed a double runner, provided on the inner face of its rim or rims which overhang the steam jet devices, with two annular sets of buckets, the one set arranged to face in a direction opposite to that of the other, so that the runner may be caused to revolve in one direction or the other, according to which set of buckets is acted upon by the steam jet. The object of my invention is to produce a 10 simple, economical and efficient steam turbine of this type, to which end it consists of certain improvements which will first be described in connection with the accompanying drawings forming part of this specification, and will then be more particularly pointed out in the claim.

In said drawings—

Figure 1 is a side elevation, partly in section of a steam turbine embodying my improvements in their preferred form, the sectional portion being on line 1—1, Fig. 4.

Fig. 2, is a similar sectional elevation of the same, the line of section being on line 2—2, Fig. 4.

Fig. 3, is a horizontal cross section of the engine on line 3—3, Fig. 1.

Fig. 4 is a vertical cross section on line 4—4, Fig. 1.

A is the cylindrical casing made in two 40 parts a, a' bolted together as shown. From the interior opposite faces of the casing project steam chests B, B', each of them preferably cast integral with the part of the casing with which it is associated.

Transversely through each steam chest extends a tubular hub b and b' as shown cast in one with the body of the chest, the one hub being on the axial prolongation of the other, and the two serving as bearings 50 for the driven shaft C which passes through, and is mounted to revolve in, them—by which arrangement any leakage of steam from the steam chest at these points is effectively prevented. The hubs, b, b' , may be 55 cast solid with the steam chests with which they are respectively associated, and can

afterward be bored out to provide the tubular bearings for the driven shaft C.

On its longer axis each steam chest is prolonged symmetrically, on each side of the hub b or b' to provide a passage way for the steam jet which acts upon the buckets of the turbine wheel or runner, and a seat which the inner face of the overhanging rim of the runner snugly fits and contacts with 60 during its revolution. Such prolongations are lettered b^6, b^6 in the steam chest B and b^7, b^7 in the steam chest B'; the steam jet passage way in said prolongations is lettered b^2 in the steam chest B, and b^3 in the 70 steam chest B', and the bearing surfaces or seats at the outer extremities of said prolongations are lettered b^4 , and b^5 , for steam chests B and B' respectively.

The double runner or turbine wheel D is 75 mounted upon that portion of the shaft C which extends between the interior opposite faces of the two steam chests B, B'. Its hub d is mounted on and keyed or otherwise suitably fastened to the shaft, and its web 80 d' , of circular form, carries on its outer edge annular rims d^2 which laterally project from opposite sides of the web, so as to overhang the prolongations b , and b' of the steam chests, and to revolve over and in 85 contact with seats or bearing surfaces b^4 and b^5 at the outer ends of said prolongations b and b' respectively. The annular sets of buckets d^3 are the same in both rims save that the buckets in the one rim face 90 in a direction opposite to that in which the buckets in the other rim face, as indicated in Figs. 1 and 2; and the steam jet passage ways b^2 and b^3 of the steam chests B, B' respectively are also correspondingly reversely 95 inclined as indicated in the same figures. In each rim the annular series of buckets is formed in an intermediate portion of its inner face, leaving on each side of the buckets a smooth unbroken surface to the rim 100 which fits and revolves in close contact with seats b^4, b^5 as indicated in Figs. 1 and 4 on the steam chests, thus preventing the escape of steam which is discharged from the jets b^2, b^3 , until after the buckets shall have 105 passed beyond said seats b^4, b^5 . The double runner or turbine wheel contacts with the steam chests, only at the diametrically opposite points on the two steam chests, where the inner faces of the overhanging rims 110 meet, for a brief period during their revolution, the seats b^4, b^5 . At all other points

there is no contact, and the exhaust steam is free to circulate throughout the interior of the casing, assuring equalization of pressure upon all the moving parts therein. The 5 double runner or turbine wheel may be a single integral casting, or it may be cast separately in two parts—one for each set of buckets—suitably associated together to move as one with the shaft on which they 10 are mounted. The latter arrangement, which is on the whole to be preferred, is shown in the drawings, the double runner being there represented as made in two parts bolted together back to back. The dimensions 15 of the co-acting parts of the runner or turbine wheel and the steam jets and bearing surfaces or seats surrounding the same may be varied considerably without departure from my invention. I have obtained 20 good results from an arrangement like that illustrated in the drawing, wherein the discharge end of the steam jet is of a width equal to that of the bucket, and of a fore and aft length equal to the combined running length of the mouths of two buckets, 25 as indicated in Fig. 1; and, with a view to obtain uniform and regular propulsive impulse, I prefer to stagger the arrangement of the buckets with reference to the two 30 steam jets of each steam chest, so that when two buckets precisely fit over and cover the jet at one end of the steam chest, the jet at the opposite end of the steam chest will be in communication with three buckets, 35 the two end buckets being each half open, and the intermediate bucket being full open, to the jet.

The steam from the runner, as its buckets pass beyond the bearing surface or seat b^4 40 or b^5 , is discharged therefrom into the interior of the casing from which it is carried off through a suitably located exhaust, typified at E; the water of condensation which may form will gather at the bottom of the casing, from whence it can be drawn off when necessary through a suitable pet cock F. The steam carried off through the exhaust can be used to drive a low pressure engine or for any other desired purpose. 45

50 Steam is supplied to the steam chests through a pipe G leading from a suitable source of steam supply, one branch g of which pipe leads to steam chest B, and the other branch g' to steam chest B', opening into 55 their respective steam chests through opposite sides of the casing. At the point where the main steam supply pipe G branches, a three-way cock H is located by which steam from the main supply G can be directed into 60 either branch g or g' or shut off from both branches, at will, for the purpose of starting, reversing or stopping the engine as desired, and as usual in this class of engines.

There is a clearance space h between each 65 face of the web and the head of the steam chest which adjoins it. The interior of the hubs are lined with suitable bushings i , and spaces k are preferably left beyond the bushings and between them and the adjoining hub of the runner, for the reception of 70 thrust blocks to be interposed between the steam chest and the hub of the runner to counteract any tendency to end thrust on the part of the latter. Appropriate lubricating appliances (not shown) are of course 75 employed to ease the rotary movement of the driven shaft C in its bearings.

Having described my improvements and the best way now known to me of carrying the same into practical effect, I state in conclusion that I do not limit myself narrowly 80 to the structural details hereinbefore shown and set forth in illustration of my invention, since manifestly the same can be varied to a considerable extent without departure 85 from the spirit of the invention; but what I claim herein as new and desire to secure by Letters Patent is:

In a steam turbine the combination of a 90 casing provided with a steam exhaust; steam chests one on the inner face of each head of the casing; a shaft passing axially through the casing and steam chests and mounted in proper bearings therein; a double runner or turbine wheel comprising a 95 web mounted on and fixed to said shaft at a point between the interior opposite heads of the two steam chests, and two annular rims laterally projecting from opposite faces of the web at its periphery, and overhanging 100 the steam chests; buckets formed in the inner face of each rim which open and discharge into the space circumscribed by the rim in a direction toward the walls of the steam chest; radial and approximately diametrically opposite tubular prolongations on said steam 105 chests, terminating in nozzles for the passage of the steam jet which contact at their outer extremities alone with the inner bucketed faces of their respective rims, the 110 inclination of the one set of buckets and its coöperating steam jets being in a direction opposite to the other, and the arrangement being such that the steam which escapes from the buckets as the latter pass beyond the nozzles discharges inwardly toward and against the steam chest walls, and thence freely passes out laterally from the open space between the steam chests and the overhanging rims of the runner into the 115 interior of the casing; and means for supplying steam to one or the other of the steam chests or cutting it off from both at will. 120

In testimony whereof I hereto affix my signature:

JOHN B. McCORMICK.
